UNITED STATES PATENT OFFICE

LEE P. HYNES, OF ALBANY, NEW YORK, ASSIGNOR, BY MESNE ASSIGNMENTS, TO CONSOLIDATED CAR-HEATING COMPANY, INC., OF ALBANY, NEW YORK, A CORPORATION OF NEW YORK

ELECTRIC DOOR-OPERATING MECHANISM

Application filed March 17, 1923. Serial No. 625,868.

For a detailed description of the present form of my invention, reference may be had to the following specification and to the accompanying drawings forming a part there-
5 of, wherein

- Fig. 1 is a plan view partly in section;
- Fig. 2 is a side elevation with the motor and switches removed;
- Fig. 3 is a front elevation;
- 10 Fig. 4 is a front view of the yokes;
- Fig. 5 shows the door arm;
- Fig. 6 is an enlarged section on line $x-y$ of Fig. 1;
- Fig. 7 shows the limit switch;
- 15 Fig. 8 is a section on line $a-b$ of Fig. 1 and Fig. 9 is a circuit diagram.

For the operation of doors on railway cars and in similar situations, pneumatic motors have heretofore been universally used and 20 attempts to employ electric motors for that purpose have not proved practicable. In my application for patent Serial No. 543,079, filed March 11, 1922, I have shown and claimed an electric door motor containing in 25 the circuit a torsion switch, the two members of which are interposed in the transmission gear between the door and motor so that when the motor torque applied to the door exceeds a predetermined magnitude the 30 switch will open and break the motor circuit. The opening of that switch is resisted by a spring which reacts in both directions, against the door on the one hand and against the motor on the other hand. If the door is 35 obstructed the continued force of the motor will expend itself in stressing the spring until the switch opens and the motor current cut off. Thereupon the reaction of the spring will, if the door remains blocked, reverse me- 40 chanically the direction of rotation of the motor until the switch is again closed and its effort to move the blocked door is repeated and the switch again opened. That action will continue until the obstruction to the 45 door movement is removed and its run is completed, the motor-circuit being then finally broken by a limit-switch. My present invention includes, as an improvement on the foregoing arrangement, a device for eliminating the reaction of the aforesaid spring

on the motor, whereby the surging, to-and-fro action of the motor is avoided and the strain thereon materially reduced. Thus, in the event of the door being blocked, the motor will operate the torsion switch until its circuit is broken and will then remain stopped because the spring can not react on it to reverse its movement and reclose the switch. If, however, the door is then released, the spring, which is still able to react on the 55 door, will move it forward till the switch is again closed and the motor resumes its driving of the door. It will be recognized that the spring will have sufficient strength to move the door, upon the removal of the 60 obstruction, because it must be stiff enough to permit the driving of the door by the motor when conditions are normal and the door unobstructed without yielding enough to open the switch. The means I prefer to 65 employ for thus preventing the reaction of the torsion-switch spring on the motor consist of a worm and screw interposed in the gear train and a point between the motor and the torsion-switch. The pitch of the 70 screw will be such that, while the motor can act therethrough to compress the spring, yet if the door should become blocked, the spring can not react therethrough. Together with such a non-reacting gear I arrange the 75 spring of the torsion switch so that on one side it will react on the door and on the other side will react against a fixed abutment upon the motor to reverse its rotation. This protects the motor, as above described, 80 and, moreover, if the door should fail to operate the limit-switch, when closed or apparently closed, the motor will not be left in a condition to continue indefinitely its surging action heretofore mentioned. The limit- 85 switch may even be omitted for that direction in which the torsion-switch acts.

As a further improvement, I have also devised a form of torsion-mechanism that rotates with the shaft of the radial door arm, 90 but, when it acts, it will move axially along said shaft a pin which is concentric with the shaft and projects from the outer end thereof. This movement of the pin will serve to operate a stationary lever which, in turn, 100

will operate a snap switch in the motor circuit. By this means I avoid the necessity of providing flexible conductors to follow the torsion-switch contacts, which rotate with the said shaft, or other form of moving connection.

Referring to the drawings, F is the door-arm shaft which oscillates about 180 degrees to open or close the door through a radial door-arm H secured to disc G on the end of the said shaft F. Loose on the shaft is a sleeve K to which is keyed a gear-wheel E that meshes with a pinion D on the countershaft B. The countershaft carries a worm-wheel C engaged by a screw which is shown in dotted lines at R in Fig. 3 on the shaft of the electric motor A. Both the door-arm shaft and the countershaft are journaled in bearings formed in the casing M. It will be manifest that by the mechanism thus far described, the electric motor when acting gives rotation to the sleeve K.

On sleeve K is a radial arm P from the front of which near its outer end projects a pin 30 (shown in dotted lines in Fig. 1 and in detail in Fig. 6). The pin 30 enters an elliptical opening in one end of a yoke S whose opposite end is pivoted to one end of a similar yoke T on the aforesaid door-shaft F. At the ends opposite from the pivot the two yokes are pressed together by two oppositely acting springs 26 and 27. By this arrangement the rotation imparted to sleeve K by the electric motor is communicated, through arm P and pin 30, to the spring-pressed end of yoke S and thence, through springs 26 and 27 to the yoke T and the door-arm shaft F on which yoke T is mounted. The springs 26 and 27 are of such stiffness that under normal conditions they will transmit the motor torque to the door without yielding materially, but if the door is obstructed, they will yield and allow the end of yoke S to move away from the adjacent end of yoke T. When that occurs the yoke S will lift one end of an angle-lever U whose opposite end extends down into a recess in door-shaft F and there bears against the inner end of an axial pin W. The pin will thereby be pushed out from the end of shaft F and operate switch-lever Z whose opposite end bears against the stem 16 of the torsion-switch O. The switch O is a toggle snap-switch of a well known type which is in the main circuit of the motor and which opens that circuit when operated by lever Z under the conditions just described.

It should be observed that the ultimate thrust of springs 26 and 27 is against the door on one side and on the opposite side is against a fixed abutment, to-wit, the longitudinal thrust-bearing of the screw R, since the pitch of that screw is so steep that it cannot be rotated backward by the worm-wheel C. In that respect my present arrangement differs

from my former one wherein the back thrust of the torsion acted to mechanically rotate the motor shaft backward as soon as its circuit was broken until the torsion switch was reclosed. In my present device that switch can only be reclosed by the release and forward movement of the door, not by the reverse rotation of the motor, since the spring, on the motor side reacts against the fixed abutment, not against the motor shaft. By the present improvement the recurrent opening and closing of the motor circuit, the closing taking place while the motor was reversely rotating, is avoided and the stress on the motor materially reduced.

On the outer end of the door-shaft F is a cam Y for operating the limit switch Q through an angle-lever 8, engaging the stem 19 of that switch. In Fig. 7 the switch Q is illustrated, this figure also serving to illustrate the torsion-switch O which is the same as Q except for the omission of one of the two circuits. The stem 19 which slides through the box is forced in one direction by lever 8 and in the opposite direction by spring 42. It carries an insulating block 37 on which are pivoted the two spring-joined toggle levers 35 and 36 electrically connected by strip 34. When the door is moving towards—say its closing position the cam Y and lever 8 will be moving towards the right, the toggles 35 and 36 bearing on contacts 52 and 54 in the door-closing circuit 6—6, as shown in dotted lines. At the moment of closing, or slightly before, the toggles will pass the dead-center position and instantly snap away from contacts 52 and 54 and against contacts 51 and 53, as shown in full lines, in the door-opening circuit 5—5. The reverse action will take place when the door is moving in the opposite direction towards its full open position. Fig. 9 shows the electric circuits. I provide two separate field-magnet coils for the motor which are reversely wound, one serving to give it its opening and the other its closing direction of rotation. The door-opening coil e is included in a circuit 5—5 and the door-closing coil o in a branch circuit 6—6. The controlling-switch 12 serves to introduce the supply current to either circuit as may be desired, both circuits being completed through the torsion-switch O to the motor armature and ground.

In Fig. 5 I have shown the door 65 provided on one edge with a channel 60 in which rides a roller J on the outer end of the aforesaid arm. As the arm rotates through an arc of approximately 180 degrees, the door moves backward or forward. In the figure it is supposed to be in or approaching closely to its closing position, the arm H at this time bearing upon and tensioning a spring 64. Since this spring can not act to reverse the motor when the circuit is broken, because of the worm and screw form of gearing, the en-

ergy stored in this spring will remain therein and be utilized to aid the restart of the door in the opposite direction. The arm will also act to lock the door in each position.

5 In the door operating mechanism herein described are found features of advantage as compared with the standard pneumatically operated door, one such feature being a gain of more than twenty-five per cent. in the total time required for opening or closing of the same door. That is due to the fact that the electric door maintains a steady rate of speed from start to finish, whereas the pneumatic door requires a heavy initial air pressure for 10 starting which involves a protracted period of pressure reduction toward the latter end which is utilized for cushioning. In my electric door the torsion springs in addition to the function, heretofore described, also provide 15 an effective cushion without the retardation inherent in the pneumatic door with its extremely slow air checking such as appears in an ordinary pneumatic door-check. Moreover, by my device I am able to dispense with 20 the door shoe and its motor-controlling connection which is a highly important gain. Finally, the electric plant is compact and complete in itself and devoid of the highly complex system of relay control required in the 25 pneumatic system.

30 What I claim as new and desire to secure by Letters Patent is:

1. Electric door operating mechanism comprising a motor, a door operating shaft, non-reacting gearing interposed between the motor and said shaft, a spring interposed between said gearing and said shaft, said spring being subject to the motor torque and reacting against said shaft on one side and against a 35 fixed abutment on the other side provided by said gearing.

2. Electric door operating mechanism comprising a motor, a door operating shaft, non-reacting gearing interposed between the motor and the shaft, a spring mounted to rotate 40 with said shaft and interposed between the shaft and the gearing, said spring being subject to the motor torque and reacting against said shaft on one side and against a fixed abutment on the other side provided by said 45 gearing.

3. Electric door-operating mechanism comprising a motor, non-reacting gearing between said motor and the door, a spring interposed between said gearing and the door, said spring being subject to the motor torque and reacting against the door on one side and against a fixed abutment on the other side and a motor-controlling switch operated by 50 the yielding of the spring.

4. Electric door-operating mechanism comprising a motor, a door operating shaft, a nonreacting worm-wheel and screw gearing between the door operating shaft and the motor, and a spring interposed between the 55

motor and said shaft and subject to the motor torque and reacting against the door on one side and against a fixed abutment on the other side provided by said gearing.

5. Electric door-operating mechanism 70 comprising a motor, a radial door arm and its shaft, a second concentric shaft, a spring interposed between the two shafts, a switch operated by the yielding of said spring, and a worm-wheel-and-screw gearing between said second shaft and the motor.

6. Electric door-operating mechanism 75 comprising an electric motor, a non-reacting gearing between said motor and the door including a rotating shaft with a member movable axially thereon, a switch operated by said member, an interposed spring in said gearing, and means for operating said member by the yielding of said spring.

7. Electric door-operating mechanism 80 comprising a motor, a door-operating arm with a shaft therefor, a yoke member on said shaft and rotating therewith, a second yoke member driven by the motor through a worm-wheel-and-screw gear, a spring connecting the two yoke members, and a motor-controlling switch operated by the relatively movement of the yokes.

8. Electric door-operating mechanism 85 comprising a motor, a door-operating arm with a shaft therefor, a second shaft sleeved on the arm-shaft, a countershaft geared to said sleeving shaft and operated by the motor through a worm-wheel and screw, yoke members connected respectively to the door-arm shaft and the sleeving shaft, a spring between the two yokes and a motor-controlling switch operated by the relative movement of the yokes.

9. Electric door-operating mechanism 90 comprising a motor, a door-operating arm with a shaft therefor, a parallel shaft driven by the motor through a worm-wheel-and-screw gear, spring connected yokes one on the end of the door-arm shaft remote from the door the other driven by the said parallel shaft, a pin in the end of the door-arm shaft operated by the relative movement of the two yokes, and a stationary motor-controlling switch operated by said pin.

10. Electric door-operating mechanism 95 comprising a motor, a door-operating arm with its shaft, two spring-connected yoke members one mounted on the door-arm shaft the other driven by the motor, a longitudinally moving member on the said shaft, a lever between said member and the yoke-members, a stationary motor-controlling switch, and an operating lever for said switch engaged by said longitudinally moving member on the door-arm shaft.

11. Electrical door-operating mechanism 100 comprising a motor, a door-operating arm with its shaft, a sleeving shaft concentric 105

with said door-arm shaft, a gear wheel on said shaft adjacent to the door-arm, a counter-shaft having a pinion engaging the said gear wheel, a worm-wheel-and-screw gear between said countershaft and the motor, a spring connection between the outer ends of said door-arm and sleeving shafts, and a motor-controlling switch operated by the yielding of said spring connection.

13. 12. Electric door-operating mechanism comprising a motor, a door-operating arm with its shaft, a sleeving shaft on the door-arm shaft driven by the motor through a non-reacting gearing, a spring connection between said shafts, a motor-controlling switch operated by the yielding of said spring connection and limit switches for the motor operated by the door-arm shaft.

13. 13. Door-operating mechanism comprising an electric motor having separate field magnets for each direction of movement, a switch for directing current through either of said field magnets, a limit-switch in each field-magnet circuit operated by the motor alternately, spring-connected members one driven by the motor and the other driving the door, and a control switch for the motor operated by the relative movement of said spring connected members when movement of the door is obstructed.

14. 14. Door-operating mechanism comprising a motor, a door-operating arm, spring means interposed between said arm and said motor so that said arm may be driven by said motor, a channel on the rear edge of the door, and a roller on the end of the door arm traveling longitudinally in said channel.

15. 15. Door operating mechanism comprising an electric motor, a door operating shaft, a non-reacting gearing between said motor and said shaft, and a spring stressed by any tendency to move the shaft to door opening position, and reacting on one side against said door operating shaft and on the other side against a fixed abutment provided by said gearing.

16. 16. Door-operating mechanism comprising an electric motor having a branching circuit, separate field magnets in the respective branches one for each direction of rotation, a switch for directing current through either of the said branches, a limit switch in each branch, and in the unbranched portion of the said circuit the motor armature and a torsion switch operated by the stress of the motor upon the door when movement of the door is obstructed.

17. 17. A door operating mechanism comprising a rotatable shaft, a radially disposed door arm secured to said shaft so as to be non-rotative with respect thereto, an electric motor, a non-reacting gearing driven by said motor, and a spring mounted to rotate with said shaft and interposed between the shaft

and the gearing so as to operatively connect them.

Signed at Albany, county of Albany, State of New York, this 14th day of March, 1923.
